(57) **CLAIM**

The ornamental design for a workstation for supporting materials, equipment, and the like on a ladder, as shown and described.

DESCRIPTION

FIG. 1 is a top, rear, and left side perspective view of a workstation for supporting materials, equipment, and the like on a ladder showing my new design;

FIG. 2 is a top, front, and right perspective view thereof;

FIG. 3 is a front view thereof;

FIG. 4 is a right side view thereof;

FIG. 5 is a top view thereof;

FIG. 6 is a rear view thereof;

FIG. 7 is a left side view thereof; and,

FIG. 8 is a bottom view thereof.

The broken lines shown in the figures are for the purpose of illustrating portions of the workstation for supporting materials, equipment, and the like on a ladder and form no part of the claimed design. The broken lines showing a ladder in FIG. 1 are for the purpose of illustrating environment which forms no part of the claimed design.

1 Claim, 8 Drawing Sheets
